This is a continuation-in-part of my application, Serial No. 789,076, filed December 1, 1947, and entitled "Sectional Ladder," which application is now pending.

This invention relates to a ladder and more particularly to a step ladder.

UNITED STATES PATENT OFFICE

2,517,991

SECTIONAL LADDER

Alfred W. Eddy, Chicago, Ill.

Application December 1, 1947, Serial No. 789,076

5 Claims. (Cl. 228—26)

1

This invention relates to a ladder and more particularly to a step ladder. More specifically this invention relates to a step ladder consisting of a plurality of sections arranged to be connected together for increasing the vertical extent of the ladder.

It is a well known fact that one or more step ladders are usually included in the various maintenance implements appurtenant to a home or place of business. Ladders thus utilized are usually of standard height so that they may readily be stored in out of the way places when not in use. The need, however, often arises for a ladder of unusual height and when this occurs the conventional size ladder cannot effectively be used. To maintain ladders of unusual height would be an expensive and inconvenient procedure for the owner and he thus generally finds himself with a problem that cannot be solved with the standard step ladders that he maintains on hand. Applicant has therefore perceived the need and has solved this problem by a novel improved step ladder construction which can quickly and inexpensively be set up for use where increased height in the ladder is necessary. It is applicant's prime object therefore to provide an improved sectional ladder construction.

Another object is to provide a plurality of conventional size step ladder constructions, said ladder constructions being designed so that they may be readily disassembled into sections and reassembled to provide a step ladder of increased height or vertical extent.

Another object is to provide a step ladder having side members and ladder supports, said side members and ladder supports being formed of a plurality of quick detachable sections.

Still another object is to provide a sectional step ladder having an improved bracket construction for connecting said sections together in a sturdy inexpensive and effective manner.

These and other objects will become more clearly apparent from a reading of the following description when examined in conjunction with the drawings.

In the drawings:

Figure 1 is a side elevational view of a step ladder of conventional size height, said ladder including bracket members adapted to be utilized in connecting sections thereto;

Figure 2 is a front view of the step ladder shown in Figure 1;

Figure 3 is a front view of a step ladder, said ladder having a greater base width than the ladder shown in Figure 2;

Figure 4 is a front view of a step ladder, said ladder having a greater base width than the ladder shown in Figure 3;

Figure 5 is a side elevational view of a step ladder including a plurality of sections connected thereto for increasing the vertical height of the same;

Figure 6 is a perspective view of a portion of a section attaching bracket;

Figure 7 is a sectional view taken along the line 7—7 of Figure 5;

Figure 8 is a detail side elevational view of a portion of a section attaching bracket;

Figure 9 is an end view of the same;

Figure 10 is a side elevational view of a brace member;

Figure 11 is a sectional view taken along the line 11—11 of Figure 10.

Referring particularly to Figures 1 and 2, a ladder of conventional height is designated by the reference character 10. The ladder 10 comprises an upper step 11 to which are connected a pair of angle members 12. A pair of upright or side members 13 are rigidly connected at their upper ends to the step 11 in a conventional manner by bolts or other securing means. The side members 13 diverge or slope outwardly, their spacing at the lower end being considerably wider than at the top. A plurality of steps 14 are connected to the side members and are in turn supported by reinforcing rods 15.

A pair of ladder supports 16 are pivotally connected at their upper ends to the angle members 12. The ladder supports include cross members 16', and are positioned to diverge outwardly in the same manner as the side members 13.

Referring to Figures 3 and 4, ladders 20 and 21 are similarly constructed to ladder 10. These ladders include upper steps 22 and 23 having angle members 24 connected thereto. Side members 27 and 28 are connected to the steps 22 and 23. Each pair of side members also respectively includes steps 29 and 30 and ladder supports 31 and 32. The side members 27 and 28 are broken away as shown in Figures 3 and 4 to more clearly indicate the ladder supports which are positioned directly behind these members.

The step ladders 10, 20, and 21 are all of conventional height and construction so that they can all be generally used in projects where the same working height is involved. Because of their size they can readily be stored by the user.

When the user needs a ladder of unusual height he can readily accomplish his purpose by the utilization of the ladders with a number of minor

adjustments. By disconnecting the side members 27 and 28 respectively from the upper steps 22 and 23 he thereby provides ladder sections which are designated A and B. By also disconnecting ladder supports 31 and 32 respectively from steps 22 and 23, he thereupon provides ladder support sections designated C and D.

The ladder section A and support section C are narrow in width at the top and wider at the bottom. The upper ends of the side members 27 of section A are placed into engagement with the lower ends of the side members 13 of the ladder 10 to that the members are engaged in overlapping relation. This relation is best shown in Figure 7. The section B is joined to the lower end of section A in a similar manner to provide for the extension of the ladder as indicated in Figure 5. The support sections C and D also have their ends in overlapping relation to join the parts together and thus provide a firm structure.

In order to properly splice the ends of the sections to one another in overlapping relation, a bracket designated generally as 40 is provided. A bracket 40 is provided for each splice and since the brackets 40 for securing the ladder supports are similar in structure to the ones required for securing the side members, the same reference characters will be used for both types.

Each bracket 40 consists of a pair of channel members 41 having leg members 42. The leg members 42 are bent inwardly toward one another so that they overlie sides of the side members or ladder supports as illustrated in Figure 7. Each channel member is of sufficient length to firmly connect the sections to one another.

A plate member 43 is placed between the ends of the side members or ladder supports. Each plate member is provided with flange portions 44 which extend angularly outwardly in opposite directions. These flange portions 44 are positioned so that they engage edges of the side members or ladder supports. They are rigidly held against the edges of the ladder support or side members by means of the channels 41 which have their legs 42 overlapping the flange portions 44. A plurality of securing members or bolts 45 extend through the channels 41, the side members or ladder supports, and the plate 43 for effectively connecting the members together. It can clearly be seen that the relation of parts is such that a sturdy box section is provided.

A brace 50 consisting of brace links 51, has its ends pivotally connected to the plate members 43 as best shown in Figures 5 and 8. The brace 50 extends between ladder supports and the side members for reinforcing the same and securing the ladder in an open working position. A U-shaped clip 52 and rivet 53 connect the links 51 in pivotal relation so that the ladder may be closed up in a conventional manner.

The connection of the brace 50 to the plate members 43 is of prime importance since this provides for a safe and rigid connection to the box structure provided by the bracket 40.

The connection of the sections to one another or to the upper steps can be by bolts or other securing means whereby the parts may be readily assembled or disassembled. In the present disclosure bolts and nuts are shown.

It can now be seen that a novel construction has been provided wherein a plurality of conventional size ladders may quickly be converted to a sectional ladder of increased height to accommodate more unusual working conditions. The conventional size ladders can easily be stored

and yet the owner is assured of their use for many different working conditions.

By the unique and novel bracket construction for joining the sections a rigid structure is provided in an inexpensive and simple manner. By means of this construction quick assembly and disassembly is accomplished.

It is to be understood that modification and changes may be made in this construction which do not depart from the spirit of the invention as disclosed or as defined within the scope of the appended claims.

I claim:

1. A sectional ladder having a pair of upright laterally spaced side members and a pair of inclined ladder supports connected thereto, said side members and ladder supports being formed of upper and lower sections, the upper ends of the lower sections and the lower ends of the upper sections being positioned in overlapping relation, means for connecting said sections together comprising a plate member positioned between each of the overlapping ends of the upper and lower sections, said plate member having flange portions overlying edge portions of the sections adjacent the ends thereof, a brace extending between said ladder supports and said side members, said brace being connected to said plate members, a pair of channel shaped members overlapping each of the upper ends of the lower sections and each of the lower ends of the upper sections, said channel members having legs projecting inwardly toward each other for engaging and overlying the flange portions, and securing means for connecting the members together.

2. A sectional ladder having a pair of upright laterally spaced side members, said side members being formed of upper and lower sections, the upper ends of the lower sections and the lower ends of the upper sections being positioned in overlapping relation, means for connecting the sections together comprising a plate member positioned between each of the overlapping ends of said sections, said plate member having flange portions overlying edge portions of the sections adjacent the overlapping ends, a pair of channel shaped members having legs projecting inwardly toward each other, the legs engaging the edge portions of the sections adjacent the overlapping ends, and securing means for connecting said members together.

3. A sectional ladder having a pair of upright laterally spaced side members, steps connecting said side members, said side members being formed of upper and lower sections, the lower ends of the upper sections engaging the upper ends of the lower sections in overlapping relation. A box structure at the overlapping ends of each section for securing the sections together, said structure comprising a plate member lying between the overlapping ends of the sections and having flanges overlying edges of said sections adjacent the overlapping ends, a pair of channel shaped members oppositely disposed with respect to each other, said channel shaped members having legs projecting toward each other and engaging edges of said side members, and securing means extending through the channel members and said plate member for connecting said members together.

4. A pair of first and second short step ladders adapted to be assembled together to form a single step ladder of greater height than each of said step ladders, each of said step ladders

comprising laterally spaced side members connected together by steps to form side member sections, laterally spaced ladder supports pivotally connected to upper ends of the side members to form ladder support sections, the side member sections and the ladder support sections having a relatively narrow spacing at their upper ends and a substantially wider spacing at their lower ends whereby the side members diverge outwardly with respect to each other and the ladder supports diverge outwardly with respect to each other, each of said ladders including a horizontally extending top step connected adjacent the upper ends of the sections, means on the second of said ladders detachably connecting the upper end of the side member sections to the upper ends of the ladder support section whereby the second ladder may be disassembled into respective separated sections, means for connecting the upper ends of the separated sections of the second step ladder to the lower ends of the sections of the first step ladder in overlapping relation, said means including connecting members on the separated sections of the second step ladder disposed adjacent the upper ends thereof, connecting members on the sections of the first step ladder adjacent the lower ends thereof, and means securing the connecting members together, whereby the side members of the first and second ladders and the ladder supports of the first and second ladders are connected in overlapping longitudinally adjacent relation, the side members of the first ladder and the side members of the second ladder diverging in the same longitudinal direction to provide a single ladder of increased height, the single ladder having its side members spaced relatively narrow at the upper end of the ladder and its side members spaced relatively wide apart at the lower end of said ladder.

5. A pair of first and second short step ladders adapted to be assembled together to form a single step ladder of greater height than each of said step ladders, each of said step ladders comprising laterally spaced side members connected together by steps to form side member sections, laterally spaced ladder supports pivotally connected to upper ends of the side members to form ladder support sections, the side member sections and the ladder support sections having a relatively narrow spacing at their upper ends and a

substantially wider spacing at their lower ends whereby the side members diverge outwardly with respect to each other and the ladder supports diverge outwardly with respect to each other, each of said ladders including a horizontally extending top step connected adjacent the upper ends of the sections, means on the second of said ladders detachably connecting the upper end of the side member sections to the upper ends of the ladder support section whereby the second ladder may be disassembled into respective separated sections, means for connecting the upper ends of the separated sections of the second step ladder to the lower ends of the sections of the first step ladder, said means including connecting members on the separated sections of the second step ladder disposed adjacent the upper ends thereof, connecting members on the sections of the first step ladder adjacent the lower ends thereof, and means securing the connecting members together, whereby the side members of the first and second ladders and the ladder supports of the first and second ladders are connected in longitudinally adjacent relation, the side members and the ladder supports of the first ladder and the side members and ladder supports of the second ladder diverging in the same longitudinal direction to provide a single ladder of increased height, the single ladder having its side members and its ladder supports spaced relatively narrow at the upper end of the ladder and its side members and ladder supports spaced relatively wide apart at the lower end of said ladder.
